Fleming & Hansen
Inventor

UNITED STATES PATENT OFFICE.

THORVALD HANSEN, OF EVERETT, MASSACHUSETTS, ASSIGNOR, BY MESNE ASSIGNMENTS,
TO STANDARD FIBRE COMPANY, INCORPORATED, OF SOMERVILLE, MASSACHUSETTS.

COLLAPSIBLE MANDREL.

No. 899,530.

Specification of Letters Patent. Patented Sept. 29, 1908.

Application filed October 25, 1905. Serial No. 284,344.

To all whom it may concern:

Be it known that I, THORVALD HANSEN, a citizen of the United States, residing at Everett, in the county of Middlesex and State of Massachusetts, have invented a new and useful Improvement in Collapsible Mandrels, of which the following is a full, clear, and exact description, reference being had to the accompanying drawings, forming a part 10 of this specification, in explaining its nature.

In the process of manufacturing vulcanized fiber tubes and roving cans it is customary to form the crude tube by winding a wet and softened web of suitable fibrous material around a mandrel. During the winding operation the different layers of material are compressed and consolidated into a homogeneous tube by the action of a heated calender roll pressing toward the mandrel. The heat 20 of this calender roll causes the tube to shrink considerably so that it grips the mandrel so tightly that it is impossible to remove the tube unless some means are provided to allow the mandrel to collapse.

My invention relates to a device that overcomes these difficulties by providing means to forcibly draw the segments of the mandrel toward each other, thus freeing the tube at some section of its internal circumference and 30 enabling the remaining portion to be easily separated.

Referring to the drawings—Figure 1 is a longitudinal sectional view of a mandrel embodying my invention. Fig. 2 is a sectional view on the line 2—2 of Fig. 1, looking to the left, and shows the hinges and clips more fully described hereinafter. Fig. 3 is a sectional view on line 3—3 of Fig. 1 looking to the left. Fig. 4 is a view similar to Fig. 2 40 with the exception that the segments are shown in a collapsed position.

A is a cylindrical tube of steel, cast iron, or other suitable material which is divided longitudinally to form sections or segments 45 which may be of any number or size, but preferably constructed as shown, there being three A¹, A², A³, one A¹ having a substantially semi-circular cross section, the others A², A³ forming the remainder of the circumference. Upon the inside of the semi-circular segment A¹ are located a number of 50 hinges B which serve to pivotally attach the segments A² and A³ to A¹.

The hinges B are preferably constructed

double as shown, each having a middle leaf 55 B¹ and two flanking leaves B² and B³, the joints in the hinges being located at the edges of the semi-circular segment A¹. The segments A² and A³ are beveled as shown in Figs. 2, 3, and 4, to enable the segment A² to move 60 inward past the segment A³ when it is desired to remove a completed tube from off the cylinder.

C are clips or springs that perform the function of drawing the segment A³ inward 65 when the segment A² is operated by the means to be subsequently described.

To support the cylinder, heads D are provided, each having a flange D¹ which serves the dual purpose of centering the segmental 70 cylinder while the softened web is being wound, and preventing the segments from opening outward. Adjacent to the heads and rigidly attached to the segment A¹ are two brackets E provided with bearings E¹ 75 which prevent the shaft from becoming displaced when the heads D are removed.

D² are hubs to the heads that may serve as bearings for the mandrels.

In order that the segments A² and A³ may 80 be forcibly drawn inward away from the wound web, eccentrics F are provided which are rigidly mounted on the shaft G journaled in the hubs D². Each eccentric has an eccentric strap F¹ which pivotally connects it 85 by the pin F² to the lug F³ mounted on the segment A².

The operation of my invention is as follows:—The mandrel being set up as shown in Fig. 1 with a completed tube on the cylinder 90 A, the shaft G is rotated by any suitable means such as a crank causing the eccentrics and straps to draw the segment A² and by means of the clips C the segment A³ inward 95 toward the shaft, thus loosening the tube from the surface of the cylinder A. The heads D may then be removed and the tube drawn off the cylinder.

While I have described my invention as comprising three segments and have shown 100 three eccentrics as the means for operating them, I do not wish to limit myself to that number of segments or to that specific means for operating them, as it is apparent that any number of segments may be used and that 105 any operating means may be employed without departing from the spirit of my invention.

What I desire to secure by Letters Patent

1. In a mandrel of the character specified, the combination of a collapsible cylinder, a removable head to said cylinder having a flange projecting over the end thereof, said head forming in part one of the bearings for said cylinder, and means for collapsing the cylinder whereupon said head may be removed.
2. In a mandrel of the character specified, the combination of a collapsible cylinder, bearings therefor, a shaft mounted in said bearings, and means connecting with the uncollapsible portion of said cylinder and providing an auxiliary support for said shaft for retaining the same in proper position upon the removal of its said mounting.
3. In a mandrel of the character specified,

the combination with a collapsible cylinder 20 of bearings therefor, a shaft mounted in said bearings, eccentrics rigidly mounted upon said shafts, and eccentric straps connecting with the collapsible portion of the cylinder.

4. In a mandrel of the kind described, a 25 collapsible cylinder comprising two pivotally mounted inwardly swinging segments, a shaft concentrically located in said cylinder having eccentrics provided with eccentric straps, said straps being pivotally connected 30 to one of said segments, and means connecting the two segments to swing them inwardly simultaneously.

THORVALD HANSEN.

In presence of—

GEORGE O. G. COALE,
M. E. FLAHERTY.
